(74) Attorney, Agent, or Firm — Dickinson Wright PLLC;
Andrew D. Dorisio(57) **CLAIM**

The ornamental design for a bottle, as shown and described.

DESCRIPTION

FIG. 1 is an exploded top perspective view of a bottle, showing my new design;

FIG. 2 is an exploded front view thereof;

FIG. 3 is an exploded rear view thereof;

FIG. 4 is an exploded left side view thereof;

FIG. 5 is an exploded right side view thereof;

FIG. 6 is a top view thereof; and,

FIG. 7 is a bottom view thereof.

The broken lines in the figures illustrate the portions of the bottle and form no part of the claimed design.
